Primary Examiner — W. A. Teddy Falloway(74) *Attorney, Agent, or Firm* — Lee, Hong, Degerman, Kang & Waimey(57) **CLAIM**

The ornamental design for a razor package, as shown and described.

DESCRIPTION

FIG. 1 is a perspective view of a razor package showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another front view showing the razor package in context with a razor therein.

The broken line showing of a razor in FIG. 8 illustrates environmental structure. All other broken lines illustrate portions of the razor package. The broken lines form no part of the claimed design.
